UNITED STATES PATENT OFFICE.

MARTIN M. SCHULLER, OF CHICAGO, ILLINOIS.

SHINGLE-FASTENING DEVICE.

No. 811,445.

Specification of Letters Patent.

Patented Jan. 30, 1906.

Application filed March 6, 1905. Serial No. 248,698.

To all whom it may concern:

Be it known that I, MARTIN M. SCHULLER, a citizen of the United States, residing at Chicago, in the county of Cook and State of Illinois, have invented certain new and useful Improvements in Shingle-Fastening Devices; and I do hereby declare the following to be a full, clear, and exact description of the invention, such as will enable others skilled in the art to which it appertains to make and use the same.

My invention relates to a novel construction in a device for securing the ends of shingles on buildings to prevent warping or loosening of same, the object being to provide a cheap and efficient device of this character; and it consists in the features of construction and combinations of parts hereinafter fully described and claimed.

In the accompanying drawings, illustrating my invention, Figure 1 is a fragmentary view of the gable-roof of a cottage having its shingles fastened by means of my fastening devices. Fig. 2 is a detail fragmentary section, on an enlarged scale, on the line 2 2 of Fig. 1. Fig. 3 is a fragmentary detail perspective view, on an enlarged scale, illustrating the construction and manner of mounting of my fastening device.

Shingle roofs become leaky by reason of the fact that the shingles warp, so that the corner portions of the free ends thereof extend upwardly and leave free spaces through which a high wind easily drives the rain, and these same free spaces also offer means for excessively high winds to tear the shingles from the roof.

My present device is designed to prevent such leakage and tearing off of shingles and, furthermore, to greatly lengthen the life of the roof, and to this end consists of a strip A of relatively light sheet metal which is provided on one edge at regular intervals with tongues B, the free ends of which are pro-

vided on their side edges with V-shaped projections C, extending at right angles to the planes of the tongues B. The said tongues B extend at substantially right angles to the plane of the strip, and when the latter is secured to the roof by means of nails D, passing through perforations E provided therefor, said tongues B will serve as a gage to determine the position of the next row of shingles, said strip being mounted upon the middle portion of the preceding row of shingles, and said nails D passing through the latter and into the planks supporting said shingles. As each shingle of the next row is secured the tongues B are forced over upon the same and the projections C driven into the free end portion of the same.

My said device is very simple, cheap, and efficient.

I claim as my invention—

1. A shingle-fastening device comprising a strip of sheet metal secured to the roof underneath the free ends of each row of shingles and provided with projecting tongues bent over upon the free end portions of said shingles, and projections on the free ends of said tongues adapted to be driven into said shingles to secure said tongues.

2. A shingle-fastening device comprising a strip of sheet metal secured to the roof underneath the free ends of each row of shingles, and provided with projecting tongues bent over upon the free end portions of said shingles, and V-shaped projections on the side edges of said tongues at their free ends adapted to be driven into the free end portions of said shingles to secure the same.

In testimony whereof I have signed my name in presence of two subscribing witnesses.

MARTIN M. SCHULLER.
